BALING PRESS

Original Filed May 2, 1922 2 Sheets-Sheet 2

UNITED STATES PATENT OFFICE.

THEODORE WILLIAMS AND CLARENCE A. SWART, OF SYRACUSE, NEW YORK, AS-SIGNORS, BY MESNE ASSIGNMENTS, TO ECONOMY BALER COMPANY, OF ANN ARBOR, MICHIGAN, A CORPORATION OF MICHIGAN.

BALING PRESS.

Continuation of application Serial No. 557,890, filed May 2, 1922. This application filed September 24, 1923. Serial No. 664,334.

Our invention relates to baling presses and more particularly to power driven presses and is a continuation of application of Theodore Williams, Hermann Hill and Clarence A. Swart, Serial No. 557,890, filed May 2, 1922.

The object of our invention is to provide means for swinging the baling plunger or platen clear of the top of the baling chamber, thus permitting loading or charging of the baling chamber from the top thereof.

In the accompanying drawings forming part of this specification:

Figure 1 is a side elevation of the baling press embodying our invention showing the plunger in full lines in vertical position at one side of the baling chamber, and in dotted lines in horizontal position within the baling chamber;

Figure 2 is an end view of the press looking at the motor end thereof, the plunger member being shown in dotted lines, in lowered horizontal position within the baling chamber;

Figure 3 is a horizontal sectional view through the baling chamber;

Figure 4 is a detail sectional view showing the position of the plunger bar when the plunger member is in lowered horizontal position within the baling chamber; and

Figure 5 is a detail view showing the pitmen and plunger bar connection.

Referring more particularly to the drawings wherein like reference numerals denote corresponding parts throughout the several views, 1, represents a base comprising a bed plate 2, in the form of a steel casting, adapted to rest upon the spaced I beams 3 and 4. A plurality of short transverse slats 5, which rest upon and are suitably connected to the bed plate, form the platen of the baling chamber, to be referred to hereinafter.

Resting upon and suitably secured to the slats 5, as by braces 18, is a baling chamber 6, the end walls 7 and 8 of which each comprise two metal plates 9 and 10 respectively. The side walls 11 and 12 each comprise a single plate 12 and 13 hingedly connected to the plates 10, of the end wall 8, as at 14 and 15 respectively to permit of access to the baling chamber from the sides thereof. The plates of each end wall are spaced apart at

their inner adjacent edges to provide vertical aligned slots 16 and 17 at opposite ends of the baling chamber, for a purpose herein- 55 after described. Brace rods 19 and 19' supported in brackets 90 and 90' are provided for connection and bracing the plates of the respective end walls.

The bed plate 2, is formed at opposite ends 60 with bearings 20 and 21 preferably cast integral therewith in which vertical screws 22 and 23 are rotatably mounted. Connected to the lower extremities of the respective screws are large bevel gears 25 and 26, meshing with bevel pinions 27 and 28 fixed to opposite ends of the horizontal shaft 29, in turn rotatably mounted in brackets 30 and 31 secured to the bottom of the bed plate 2. A spur gear 32, fixed on that end of the shaft 29, to which the pinion 28, is secured meshes with the pinion 33, on the drive shaft 34 of the motor 35.

The piston or plunger member of the press comprises what may be termed a plunger bar 36. This plunger bar is preferably formed of two strips or members 37 and 38 having offset extremities 39 and 40, thus in effect forming a plunger bar with forked ends when the intermediate portions of the aforesaid strips or members 37 and 38 are placed in juxtaposed position as illustrated in Figure 4. It will of course, be understood that the bar 36, may be formed of a single casting having forked ends. Suitably secured to the bar 36, by any means (not shown) is a steel plate 39', to the bottom face of which slats 40', similar to the slats 5, are bolted, as at 41. This entire piston or plunger member is supported by two pair of 80 pitmen rods 42 and 43, which are secured to and carry at their upper or outer free ends trunnion heads 44 and 45, which the forked ends of the plunger bar 36 embrace and to which they are bolted or otherwise suitably secured. The opposite or lower ends of the pitmen rods are journaled on the trunnions 46 and 47 of nuts 51 and 52 in turn threaded- 90 ly mounted on the respective screws 22 and 23, the nuts being free to move up and down upon the screws when the latter are turned, but are locked against turning movement by reason of their engagement with the pairs of oppositely disposed guide strips

95
100

53 and 54 secured to the respective brackets 90 and 90'. The strips 53 and 54 enter oppositely disposed recesses 55 and 56 in the respective nuts, the latter being free to slide up and down with respect to the said strips.

10 The intermediate portion of the plunger bar spans the baling chamber, the forked end of the bar projecting out through the slots 16 and 17 on opposite ends of the chamber.

15 It will be understood that simultaneous rotation of the screws 22 and 23 in the appropriate direction by means of the motor 35, and gearing previously described, will cause the pitmen, and consequently the plunger bar and attached parts to ride upwardly on the screws. As the plunger bar emerges from the slots 16 and 17 it is engaged by the curved deflector arms or guides 57 and 58, 20 bolted to and projecting upwardly and inwardly from the strips 53 and 54, and is thus thrown over to one side upon the curved tracks 59 and 60, secured to the upper ends of the end walls of the baling chamber. Further rotation of the screws causes the plunger bar to travel over the curved tracks 59 25 and 60 until the pitmen 42 and 43 come in contact with the fulcrum blocks 61 secured to certain of the guide strips 53 and 54. As 30 the nuts 51 and 52 continue to rise the pitmen fulcrum on these blocks until a horizontal or Figure 2 position is reached by the pitmen, at which point the power is cut off automatically by any suitable trip mechanism (not shown) or the power may be 35 cut off manually in an obvious manner.

40 When the pitmen reach a horizontal position the plate 39' and slats 40' assume a vertical position outside the chamber 6, and consequently permit of a charge of material being fed therein at the top. It is also to be noted that the curvature of the tracks 59 and 60 is such that the plunger bar at no point in its travel is self locking. Consequently when the motor is reversed and the 45 screws rotated in a reverse direction to that just described, the plunger bar will be caused to ride back over the curved tracks until the plunger rod again enters the slots 16 and 50 17.

Having thus described our invention what we claim as our invention is:

55 1. In a baling press, the combination with a chamber having an open end, of a platen movable transversely of said chamber beyond said open end and also movable within said chamber, a screw rotatably connected to said platen for actuating the same, and a guide for automatically compelling said 60 platen to move transversely of said open end upon movement of said platen from

within said chamber through said open end.

2. In a baling press, the combination with a chamber having an open end, of a platen movable transversely of said chamber beyond said open end and also movable within 65 said chamber, a rotatable screw, a nut threaded upon said screw, means for pivotally connecting said platen to said nut, and means dependent upon the rotation of said screw for automatically compelling said platen to move laterally of said open end.

3. In a baling press, the combination with a vertical baling chamber having an open upper end, of vertical screws at opposite 75 ends of said baling chamber, a platen adapted to be raised and lowered within said chamber by said screws, and a guide for automatically compelling said platen to move laterally over and beyond the upper end of 80 said chamber upon movement of said platen from within said chamber through said open end.

4. In a baling press, the combination with a chamber having an open end, of a platen movable transversely of said chamber beyond said open end and also movable within 85 said chamber, a screw connected to said platen for actuating the same, and means for compelling said platen to move transversely of said chamber beyond said open end to open position upon rotation of said screw in one direction and to return into registration with said open end upon rotation of said screw in the opposite direction. 90

5. In a baling press, the combination with a chamber having an open end, of a screw, and a platen connected to said screw and movable within said chamber and also automatically movable transversely of 100 said chamber beyond its open end.

6. In a baling press, the combination with a chamber having an open end, of a screw and a platen adapted to extend transversely of said chamber when in operative position 105 and to extend approximately parallel to a wall of said chamber when in inoperative position, said platen being actuated by said screw and being automatically movable to the approximately parallel position. 110

7. In a baling press, the combination with a chamber having an open end, of a platen movable laterally of said open end and also movable within said chamber, a screw connected to said platen for actuating the same, and means dependent upon rotation of said screw for compelling said platen to move laterally of said open end to open position. 115

In testimony whereof we affix our signatures.

THEODORE WILLIAMS.
CLARENCE A. SWART.
